(57) **CLAIM**

The ornamental design for a bottle, as shown and described.

DESCRIPTION

FIG. 1 is a perspective view of the bottle;

FIG. 2 is a front elevational view thereof;

FIG. 3 is a side elevational view thereof, the two sides being mirror images; and,

FIG. 4 is a top plan view thereof.

The broken lines showing in FIGS. 1, 2, 3, and 5 are for illustrative purposes only and form no part of the claimed design.

1 Claim, 3 Drawing Sheets

FIG. 1

FIG. 2**FIG. 3****FIG. 4**
